United States Patent Office

Des. 175,510
Patented Sept. 6, 1955

175,510

NECKLACE OR THE LIKE

Adolph Katz, Providence, R. I., assignor to Coro, Inc.,
New York, N. Y., a corporation of New York

Application March 8, 1955, Serial No. 34,933

Term of patent 7 years

(Cl. D45—16)

Fig. 1 is a plan view of a necklace or the like showing my new design.

Fig. 2 is an edge view thereof.

The portions of the link elements shown in full lines are repeated throughout the length of said elements as indicated by the broken line disclosure.

I claim:

The ornamental design for a necklace or the like, substantially as shown and described.
